DISPENSER

Ethel A. Field, New York, N. Y.

Application August 28, 1933, Serial No. 687,085

17 Claims. (Cl. 221—60)

This invention relates to a dispenser and more particularly to a dispensing device associated with a receptacle and operative to dispense the contents in desired quantities.

5 Receptacles used in the packaging of materials, such as tooth-paste, shaving creams and various other pastes, plastics, powders and liquids, are generally provided with a closure or cap member which is completely removed when the contents 10 are to be dispensed. The removed cap member is often dropped and sometimes lost, causing considerable inconvenience and annoyance to the user. Removable cap members in general use are also time-consuming and annoying to reapply to the receptacle.

15 Various attempts have been made to provide a closure which is fixed to the receptacle. Such devices, however have been so expensive to make as to prohibit their use as a permanent fixture to a receptacle which is normally thrown away after a single use. Many such devices heretofore provided are further objectionable in that they are 20 unwieldy and inconvenient to manipulate and leave the contents entirely or partially exposed to the atmosphere, and when operated, smear the contents around the outside of the dispensing device, presenting an unsightly and unsanitary condition.

25 It is an object of this invention to provide a dispensing device adapted to be associated with a receptacle, which is inexpensive to manufacture, neat and attractive in appearance, and which is so constructed as to prevent smearing of the contents.

30 Another object of this invention is to provide a dispensing device which will project the contents as a clean, smooth stream of desired shape and size, and which will cleanly cut the stream and close the dispensing opening by a simple finger manipulation.

35 Still another object of this invention is to provide a dispensing device which may be formed either as an integral part of a receptacle or compressible tube, or which may be formed as a separate device readily attachable and detachable to the throat or neck of the receptacle.

40 Another object of this invention is to provide a dispensing device for a receptacle comprising a cap member which encloses and protects the contents at all times, and which has associated therewith a closure member which may be easily and conveniently manipulated, by a slight movement of the finger, from closed to open position.

45 Another object of this invention is to provide a receptacle having associated therewith a closure

for the dispensing opening thereof, which may be releasably locked in closed position and in open position.

5 In accordance with this invention, a cap member or head portion is provided which may be formed as an integral portion of the receptacle, or which may be detachably applied to the receptacle as desired. The cap member comprises a body portion preferably rectangular in shape, the body portion terminating in a rounded or 10 cylindrical head portion. A dispensing opening of desired shape and form is provided in the rounded or cylindrical portion of the cap member. A closure member of U-shape form is rotatably mounted within the cap member. The 15 closure member comprises generally a blade portion contoured to slidably engage the inside surface of the cylindrical end portion so as to open and close the dispensing opening when the closure is manipulated. Flange portions extend 20 laterally from the blade portion and seat against the end walls of the body member. The closure member is rotatably mounted on suitable studs which extend through the end walls of the body portion and are fixed to the flange portions. 25 Knurled knobs fixed to the outside ends of the studs provide a convenient means for manipulating the closure member to open and close the dispensing opening. The closure member preferably rotates through a limited angle, and 30 means are provided for releasably locking the closure member in open and closed position. The cap member and closure member are preferably made of metal and may be formed by a simple stamping operation. The device is as 35 sembed by inserting the closure member within the cap member and is fixed in rotatable position by heading over the ends of the knob carrying studs which are inserted through openings provided in the body portion of the body member and in the flange portions of the closure member. The dispensing device can thus be 40 economically assembled entirely by machine operation. The device is neat and attractive in appearance, strong and durable in construction, 45 and is operative to project a clean stream of the contents in any quantity desired. The stream is cut off cleanly by a simple manipulation of the closure member without smearing the contents on the outside of the dispensing device. 50 When not in use the closure member tightly closes the dispensing opening, fully protecting the contents from contamination and exposure.

55 In order that a clearer understanding of my invention may be had, attention is hereby direct-

into the cap member and the ends of the stud elements 20 are headed over so as to form head portions 21, which portions securely connect the stud elements to the closure member. The threaded 5 collar D may then be inserted into the collar portion 13 of the cap member and fixed thereto.

There is shown in Figs. 5 and 6 a modified form 10 of dispensing device which is especially adapted for attachment to the neck of bottles and compression tubes and used in the dispensing of liquids. In the form here shown, a funnel 40 extends from the dispensing aperture 16. The lower end of the dispensing device A is provided with a collar portion 42 which snugly seats around the 15 head portion 41 of the bottle G. The bottle engaging collar portion 42 is provided with an in-turned lip portion 43 which grips the head portion 41 of the bottle G and firmly secures the dispensing device thereto.

It is understood that the dispensing device herein disclosed may be made of various modified shapes and forms most suitable for the use to which it is to be applied. The dispensing device may be formed as an integral part of the dispensing tube or receptacle or may be formed as a separate unit and then secured to the neck portion. The dispensing device may also be provided with a threaded sleeve F as shown more particularly in Fig. 4, thus making it adaptable for attachment to receptacles having threaded neck portions of different diameters. The dispensing device may be used for dispensing tooth-paste, shaving cream, creams, pastes, and plastics as well as dry or powdered materials and liquids. The dispensing device is compact and strong in construction, attractive in appearance, protects the contents from contamination and exposure, and does not smear or smudge the material ejected on the outside thereof. The device may be made 30 entirely by automatic machine operation and requires few operations, and thus is economically adapted for permanent association with receptacles and compression tubes which are thrown away after the contents have been removed.

While the dispensing device is especially adapted to be formed of stamped metal, it is understood that it may be formed of other materials, such for example as fibre, cellulose, glass, rubber and other plastic or moulded compositions and materials.

While certain novel features of the invention have been disclosed and are pointed out in the annexed claims, it will be understood that various omissions, substitutions and changes may be 55 made by those skilled in the art without departing from the spirit of the invention.

What is claimed, is:

1. A dispensing device attachable to a receptacle comprising a cap member, a dispensing opening therein, a closure for said opening rotatably mounted within said cap member and insertable into said cap member through the receptacle attaching end thereof, manipulating means external to said cap member and operably connected to said closure, and means for releasably locking said closure in closed position.

2. A dispensing device attachable to a receptacle comprising a cap member, a dispensing opening therein, a closure for said opening rotatably mounted within said cap member and insertable into said cap member through the receptacle attaching end thereof, closure manipulating means external to said cap member operably connected to said closure, means for releasably locking said closure in closed position, and

means for releasably locking said closure in open position.

3. A dispensing device attachable to a receptacle comprising a cap member having a rounded end portion, a dispensing opening in said end portion, a closure for said opening including a rounded portion contoured to slidably engage the inside surface of said rounded end portion so as to open and close said opening when the closure is manipulated, manipulating means external to 10 said cap member operably connected to said closure, and cooperating means extending from said closure and said body portion releasably locking said closure in closed and in open position. 15

4. A dispensing device comprising a cap member adapted to be fixed to the mouth of a receptacle, a dispensing opening therein, a closure for said opening including a blade portion slidably mounted within said cap member in juxtaposition 20 to said opening, closure manipulating means external to said cap member operably connected to said blade portion, and cooperating means extending from said closure and said body portion releasably locking said closure in closed and in 25 open position.

5. A dispensing device attachable to a receptacle comprising a cap member, said cap member having a rectangular shaped body portion, a cylindrical end portion, a dispensing opening in said cylindrical portion, a closure for said opening supported by and slidably connected to said cap member, said closure including a portion contoured to slidably engage the inside surface of 30 said end portion and insertable into said cap member through the receptacle attaching end thereof, and manipulating means external to said cap member connected to said closure and operable to open and close said opening. 35

6. A dispensing device comprising a cap member 40 adapted to be fixed to the mouth of a receptacle, said cap member comprising a polygonal shaped body portion and a cylindrical end portion, a dispensing opening in the cylindrical portion thereof, a closure for said opening including 45 a blade portion slidably mounted within said cap member in juxtaposition to said opening, and rotatable closure manipulating means external to said cap member operably connected to said blade portion, the circumferential width and path of 50 movement of said blade being such as to permit unobstructed passage of the contents into the cap member in all positions of the closure.

7. A dispensing device comprising a cap member 55 associated with a receptacle, said cap member having a body portion and a closed end portion, a dispensing opening in the end portion thereof, a closure including a blade portion contoured to slidably engage the inside surface of 60 said end portion to open and close said opening, and means for manipulating said blade portion, said means comprising a flange portion extending from said blade portion at right angles to the direction of movement thereof, and a finger element external to said cap member operably 65 connected to said flange portion.

8. A dispensing device associated with a receptacle comprising a cap member fixed to the receptacle, said cap member comprising a body portion and a closed end portion, a closure including 70 a blade portion contoured to slidably engage the inside surface of said end portion to open and close said opening, and means for manipulating said blade portion, said means comprising a flange portion extending from said blade portion, 75

a rotatable finger knob external to said cap member, and a shank element connecting said knob and flange portion.

9. A dispensing device associated with a receptacle comprising a cap member mounted on the receptacle, said cap member comprising a body portion and closed end portion, a U-shaped closure comprising a blade portion and a flange portion extending laterally therefrom, said blade portion being contoured to slidably engage the inside surface of said end portion to open and close said opening when the closure is manipulated, means rotatably supporting said closure, and manipulating means external to said cap member operably connected to said closure.

10. A dispensing device for a receptacle comprising a cap member mounted on the receptacle, said cap member comprising a body portion and a closed end portion, a U-shaped closure member rotatably mounted within said cap member, said closure member comprising a blade portion and flange portions extending laterally therefrom, said blade portion being contoured to slidably engage the inside surface of said end portion to open and close said opening when the closure is manipulated, and means for manipulating said closure comprising a pair of finger knobs external to said cap member operably connected to said flange portions.

11. A dispensing receptacle comprising a cap member mounted on a receptacle, said cap member comprising a body portion and a closed end portion, a dispensing opening in said end portion, a closure including a blade portion contoured to slidably engage the inside surface of said end portion to open and close said opening when the closure is manipulated, means for manipulating said closure, said means comprising a flange portion extending from said blade portion, and a finger element external to said cap member operably connected to said flange portion, and cooperating means extending from said flange portion and body portion releasably locking said closure in closed and in open position.

12. A dispensing tube comprising a body of compressible material, a head portion extending therefrom, said head portion having a cylindrical end, a dispensing opening in said cylindrical end, a closure including a cylindrical portion contoured to slidably engage the inside surface of said cylindrical end so as to open and close said opening when the closure is manipulated, manipulating means external to said cap member and operably connected to said closure, and cooperating means extending from said closure and said body portion releasably locking said closure in closed and in open position.

13. A dispensing tube comprising a body of compressible material, a head portion extending therefrom, said head portion having a cylindrical end, a dispensing opening in said cylindrical end, a closure including a blade portion contoured to slidably engage the inside surface of said cylindrical end to open and close said opening when the closure is manipulated, means for

manipulating said closure, said means comprising a flange portion extending from said blade portion substantially at right angles to the direction of movement thereof, and a finger element external to said cap member operably connected to said flange portion.

14. A dispensing tube comprising a body of compressible material, a head portion extending therefrom, said head portion having a cylindrical end, a dispensing opening in said cylindrical end, a U-shaped closure member rotatably mounted within said head portion, said closure member comprising a blade portion contoured to slidably engage the inside surface of said end portion, flange portions extending from said blade portion rotatably supporting said closure member, manipulating means external to said head portion operably connected to said closure, and means extending from said head portion releasably locking said closure in closed position.

15. A dispensing device attachable to a receptacle comprising a cap member having a rounded end portion, a dispensing opening in said rounded end portion, a dispensing funnel extending from said dispensing opening, a closure including a rounded portion contoured to slidably engage the inside surface of said rounded end portion so as to open and close said opening when the closure is manipulated, and manipulating means external to said cap member operably connected to said closure, the shape and path of movement of said rounded portion being such as to permit unobstructed passage of the contents into the cap member in all positions of the closure.

16. A dispensing device comprising a cap member having a threaded collar portion adapted to be secured to the threaded neck portion of a receptacle, a dispensing opening therein, a closure for said opening including a blade portion supported by and slidably mounted within said cap member in juxtaposition to said opening, and closure manipulating means external to said cap member operably connected to said blade portion, the shape and path of movement of said blade portion being such as to permit unobstructed passage of the contents into the cap member in all positions of the closure.

17. A dispensing device comprising a cap member having a removable threaded sleeve adapted to be secured to the threaded neck of a receptacle, a dispensing opening in said cap member, a closure for said opening including a blade portion rotatably mounted within said cap member in juxtaposition to said opening, closure manipulating means external to said cap member operably connected to said blade portion, and means for releasably locking said closure in closed and in open position, the shape and path of movement of said blade portion being such as to permit unobstructed passage of the contents into the cap member in all positions of the closure.

ETHEL A. FIELD.
